UNITED STATES PATENT OFFICE

NORRIS E. GOODRICH, OF BATTLE CREEK, MICHIGAN, ASSIGNOR TO SANITARIUM EQUIPMENT COMPANY, OF BATTLE CREEK, MICHIGAN

MASSAGING MACHINE

Application filed August 6, 1928. Serial No. 297,730.

The main objects of this invention are:

First, to provide an improved massaging machine having an adjustable stroke with means for connecting the applicator thereto which permits ready adjustment of the applicator and at the same time the possibility of the applicator becoming entangled with the revolving parts is minimized.

Second, to provide a machine of the type employing crank disks with means for connecting the applicator directly to a crank pin which minimizes the "whipping" action of the applicator.

Third, to provide an improved massaging machine which is compact and at the same time has a relatively large amount of power.

Objects pertaining to details and economies of my invention will definitely appear from the description to follow. The invention is defined in the claims.

A structure which embodies the features of my invention is clearly illustrated in the accompanying drawings in which:

Fig. 1 is a vertical section from front to rear of my improved massaging machine on a line corresponding to line 1-1 of Fig. 2.

Fig. 2 is a horizontal section on line 2-2 of Fig. 1, the cover portion of the housing being removed.

Fig. 3 is an enlarged detail section corresponding to that of Fig. 2 showing details for the mounting of the applicator attaching means on the crank pin.

Fig. 4 is a fragmentary side elevation illustrating the relation of an applicator, shown by dotted lines, to an attaching means.

Referring to the drawings, the body portion 1 of the housing is preferably in the form of a box-like casting adapted to receive the cover 2. In this housing I mount a motor shown conventionally at 3. The motor shaft 4 is provided with a pulley 5.

Disposed in parallel relation to the motor shaft 4 is a driven shaft 6 supported in bearings 7 mounted within the body portion of the housing on suitable blocks or pedestals 8. The housing has opposed openings 9 in its side walls adapted to receive the crank disks 10.

The shaft 6 is provided with a pulley 11

aligned with the pulleys 5 on the motor shaft and connected thereto by means of the belt 12 of V or triangular cross section. The crank disks 10 are provided with radial dovetailed slots 13 adapted to receive the heads 14 of the threaded studs 15, the heads of these studs being slidable in grooves.

The body members 16 of the crank pins are threaded upon these studs to clamp them in their adjusted position. These crank pin body members are chambered at 17 to receive supporting bearings for the applicator attaching studs 18. These bearings in the embodiment illustrated consist of the annular bearing members 19 secured to the body members, the inner bearing members 20 secured to the studs and the coating balls 21. The bearing members 20 are retained upon the studs by means of the washer-like plates 22 held in place by the screws 23.

A lubricant retaining ring 24 is provided to close the space between the bearing members 19 and 20 and also a closure plate 25 which is secured on a shoulder 26 within the recess of the body member by means of the screws 27 so that, while the studs project from the body members, the chambers are effectively sealed to retain lubricant.

The studs have annular grooves 28 therein to receive the eyes 29 of the spirally curved applicator attaching members 30, these eyes being formed at one end of the attaching members as is illustrated. The applicators as 31 may be engaged with these spirally formed hooks. The eyes have a friction engagement with the studs so that while they are normally fixed thereto, the hooks may in the event of undue stress rotate relative to the studs.

With the parts thus arranged the studs turn freely relative to the crank pins so that they may swing to any position and the hooks swing to whatever direction of pull there may be on the applicators.

Further, in the event of the applicators, which frequently are flexible, becoming entangled they may be passed readily from the ends of the hooks. This arrangement also has an advantage in that the "whipping" 100

action due to the direct connection of the applicator with the crank pin is minimized.

I have illustrated and described my improvements in an embodiment which I have found very satisfactory. I have not attempted to illustrate or describe other adaptations or embodiments which I contemplate as it is believed that this disclosure will enable those skilled in the art to embody or adapt the same as may be desired.

Having thus described my invention what I claim as new and desire to secure by Letters Patent is:

1. In a massaging machine, the combination of a housing having opposed openings in the side walls thereof, a driven shaft, crank disks on said shaft rotatable within said openings in said housing, said crank disks being provided with radially disposed dove-tailed ways, crank pins comprising threaded studs provided with heads slidable in said ways, body members threaded upon said studs for clamping them in their adjusted positions in said ways, said body members being chambered, studs provided with annular grooves adjacent their outer ends, ball bearings for said studs comprising outer bearing members secured within said body members, inner members secured to said studs and coacting balls, and attaching hooks having eyes at one end frictionally engaged in said grooves in said studs.

2. In a massaging machine, the combination of a housing having opposed openings in the side walls thereof, a driven shaft, crank disks on said shaft rotatable within said openings in said housing, said crank disks being provided with radially disposed dove-tailed ways, crank pins comprising threaded studs provided with heads slidable in said ways, body members threaded upon said studs for clamping them in their adjusted positions in said ways, said body members being chambered, studs, ball bearings for said studs comprising outer bearing members secured within said body members, inner members secured to said studs and coacting balls, and attaching hooks on said studs.

3. In a massaging machine, the combination of a driven shaft, crank disks on said shaft provided with radially disposed dove-tailed ways, crank pins comprising threaded studs provided with heads slidable in said ways, body members threaded upon said studs for clamping them in their adjusted positions in said ways, said body members being chambered, studs provided with annular grooves adjacent their outer ends, ball bearings for said studs comprising outer bearing members, inner members secured to said studs and coacting balls, and spirally curved attaching hooks having eyes at one end frictionally engaged in said grooves in said studs.

4. In a massaging machine, the combination of a driven shaft, crank disks on said

shaft provided with radially disposed dove-tailed ways, crank pins comprising threaded studs provided with heads slidable in said ways, body members threaded upon said studs for clamping them in their adjusted positions in said ways, said body members being chambered, studs, ball bearings for said studs comprising outer bearing members secured within said body members, inner members secured to said studs and coacting balls, and spirally curved attaching hooks on said studs.

5. In a massaging machine, the combination of a driven shaft, crank disks on said shaft provided with radially disposed dove-tailed ways, crank pins comprising threaded studs provided with heads slidable in said ways, body members threaded upon said studs for clamping them in adjusted position in said ways, said body members being chambered, applicator attaching member studs antifriction bearings by which said applicator attaching member studs are supported disposed in said chambers in said body members, closure plates for said chambers, and applicator attaching members on said applicator attaching member studs.

6. In a massaging machine, the combination of a driven shaft, crank disks on said shaft provided with radially disposed dove-tailed ways, crank pins comprising threaded studs provided with heads slidable in said ways, body members threaded upon said studs for clamping them in adjusted position in said ways, said body members being chambered, applicator attaching member studs, antifriction bearings by which said applicator attaching member studs are supported disposed in said chambers in said body members, and applicator attaching members on said applicator attaching member studs.

7. In a massaging machine, the combination of a driven shaft, crank disks on said shaft provided with radially disposed dove-tailed ways, crank pins comprising threaded studs provided with heads slidable in said ways, body members threaded upon said studs for clamping them in adjusted position in said ways, studs provided with grooves adjacent their outer ends, antifriction bearings by which said studs are supported on said body members, and spirally curved applicator attaching members having eyes at one end frictionally engaging said grooves in said studs.

8. In a massaging machine, the combination of a driven shaft, crank disks on said shaft provided with radially disposed dove-tailed ways, crank pins comprising threaded studs provided with heads slidable in said ways, body members threaded upon said studs for clamping them in adjusted position in said ways, studs, antifriction bearings by which said studs are supported on said body

members, and applicator attaching members on said studs.

9. In a massaging machine, the combination of a driven shaft, crank disks on said shaft, chambered crank pins, studs, antifriction bearings by which said studs are supported disposed in said chambers in said crank pins, closure plates for said chambers, and applicator attaching members on said studs.

10. In a massaging machine, the combination of a driven shaft, crank disks on said shaft, chambered crank pins, studs, antifriction bearings by which said studs are supported disposed in said chambers in said crank pins, and applicator attaching members on said studs.

11. In a massaging machine, the combination of a crank disk having a radially disposed dove-tailed way, a crank pin comprising a threaded stud provided with a head slideable in said way, a body member threaded on said stud for clamping it in its adjusted positions in said way, said body member having a shouldered chamber therein, a stud provided with an annular groove adjacent its outer end, a ball bearing for said stud comprising an outer bearing member secured within said chamber, an inner bearing member secured to said stud and coacting balls, and a spirally curved applicator attaching hook having an eye at one end frictionally engaged in said groove in said stud.

12. In a massaging machine, the combination of a crank disk having a radially disposed dove-tailed way, a crank pin comprising a threaded stud provided with a head slideable in said way, a body member threaded on said stud for clamping it in its adjusted positions in said way, said body member having a shouldered chamber therein, a stud, a ball bearing for said stud comprising an outer bearing member secured within said chamber, an inner bearing member secured to said stud and coacting balls, and an applicator attaching hook on said stud.

13. In a massaging machine, the combination of a crank disk having a radially disposed dove-tailed way, a crank pin comprising a threaded stud provided with a head slideable in said way, a body member threaded on said stud for clamping it in its adjusted positions in said way, said body member having a shouldered chamber therein, a stud, a ball bearing for said stud comprising an outer bearing member secured within said chamber, an inner bearing member secured to said stud and coacting balls, a closure plate for said bearing through which said stud projects secured upon the shoulder within said chamber, and an applicator attaching hook on said stud.

14. In a massaging machine, the combination with a crank disk provided with a radially adjustable crank pin, means for driving

said crank pin, a spirally curved applicator attaching hook provided with an anti-friction bearing connection with said crank pin at its shank end and disposed with the point of the hook pointing in a direction opposite to the direction of rotation of the crank pin.

15. In a massaging machine, the combination of a crank provided with a pin, means for driving said crank, and a spirally curved applicator attaching hook rotatably mounted on said crank pin with the point of the hook pointing in a direction opposite to the direction of rotation of the crank pin.

In witness whereof I have hereunto set my hand.
